[57] **CLAIM**

The ornamental design for a panel for an electrical multimeter, as shown and described.

DESCRIPTION

FIG. 1 is a perspective view of the panel for an electrical multimeter showing my new design;

FIG. 2 is a front view of the panel for an electrical multimeter;

FIG. 3 is a rear view of the panel for an electrical multimeter;

FIG. 4 is a left side view of the panel for an electrical multimeter;

FIG. 5 is a right side view of the panel for an electrical multimeter;

FIG. 6 is a top view of the panel for an electrical multimeter;

FIG. 7 is a bottom view of the panel for an electrical multimeter; and,

FIG. 8 is shown an application of the panel for an electrical multimeter.

The broken line showing is for illustrative purposes only and forms no part of the claimed design.
